UNITED STATES PATENT OFFICE

JOSEPH F. JAWOROWSKI, OF CLEVELAND, OHIO, ASSIGNOR OF FIVE-EIGHTEENTHS TO
SAMUEL E. DETTELBACH, FIVE-EIGHTEENTHS TO SAM EMERSON, AND TWO-
EIGHTEENTHS TO EDGAR HAHN, ALL OF CLEVELAND, OHIO

ROTARY PUMP

Application filed March 17, 1930. Serial No. 436,271.

This invention relates to an improvement in rotary pumps, and more particularly a pump of the type and kind shown and described in my application for patent Serial No. 243,810, filed Dec. 31, 1927, in which a pair of rotary pistons co-act with reciprocable abutment members or blades and an equalizing lever is used to control the movements of the blades. In pumps of that type the reciprocable abutment members or blades are subject to unequal strains and binding movements detrimental to the life and operation of the pump, and the equalizing lever is also easily displaced and then difficult to replace and re-align with the blades unless the whole pump is disassembled. My present object is to obviate the objections noted, first, by embodying in the pump structure means for utilizing the pressure created in the pump to counteract tilting and binding movements of the blades and to produce a smooth working action of each as well as uniform wear thereon and effective sealing results between the suction and pressure sides of the pump, and secondly, by constructing the pump body in a particular way so that the equalizing lever may be held constantly upright in free but true working alignment with the reciprocable blades, and with the parts arranged to prevent the displacement of the lever from its working place of rest when the adjusting nut and spring and/or the pressure-applying plunger associated with the lever are released or removed from the pump.

In the accompanying drawings Fig. 1 is a plan view of the pump, partly in section horizontally, on line 1—1 of Fig. 4. Fig. 2 is a sectional view horizontally of the pump on line 2—2 of Fig. 4. Fig. 3 is a cross section 40 of the pump through one of its working chambers, on line 3—3 of Fig. 4. Fig. 4 is a sectional view longitudinally through the pump on line 4—4 of Fig. 2. Fig. 5 is a sectional view transversely of the pump on the median line marked 5—5 on Fig. 4. Fig. 6 is a sectional view of the upper part of the pump, showing the equalizing lever in position without the adjusting nut, spring and plunger.

The pump comprises a main body 2 having 50 a circular chamber 3 therein which is divided

by a central wall or partition 4 to provide two working spaces 5 and 6, respectively, within which a pair of round pistons 7 and 8 are adapted to rotate. These pistons are mounted eccentrically in balanced relation on a power shaft 9 having rotatable bearing in a pair of removable end plates or heads 10 and 11, respectively, for body 2. Separate inlet and outlet ports 12 and 14, respectively, are located in opposite sides of body 2 and communicate with the working spaces 5 and 6 on opposite sides of an extension 15 of partition 4. Extension 15 is a short flat-sided bar having an enlargement 16 at one end interlocked with partition 4, and it occupies a central position within a longitudinal slot 17 which communicates at its lower end with the working spaces 5 and 6 and at its upper end with a closed compartment 18 in body 2.

A pair of flat sliding abutment members or plates 19 and 20, respectively, occupy slot 17 where divided by extension bar 15, and the reduced lower ends of these plates are adapted to project into the working spaces and have riding contact with the peripheral surfaces of the eccentric pistons, thereby separating the inlet and outlet ports completely where they communicate with the working spaces 5 and 6. Accordingly, a small area of each slideable abutment member or blade is exposed to both the suction and pressure sides of the pump and to the fluid passing through the pump. As a result the lower part of each blade is pressed constantly against one wall of slot 17 and slightly apart from the opposite wall. The rotatable movement of the pistons is also in a direction which tends to press the blades toward the suction side of the chamber and wall at that side. As a result these forces tend jointly to tilt and bind the blades slightly in the slot in operating the pump, and cause chatter and undesirable friction and wear on the parts. To counteract and eliminate the objections noted, the wall 22 on the pressure side of slot 17 is provided with one or more transverse openings 22' to permit the fluid under pressure in the outlet port 14 to press against a smaller area of the slideable blade at a point remote from the lower exposed end

of the blade, preferably against the upper half of the blade and centrally between its vertical edges, see Figs. 3 and 4, thereby holding each slidable blade in a flat seating 5 position against the opposite wall 23 and slightly apart from wall 22 during pumping operations. The slight clearance afforded between the upper half of each blade and wall 22 permits the fluid on the pressure 10 side to pass into upper compartment 18 in body 2 wherein an equalizing bar or rocking lever 24 is confined and seated at its opposite ends upon the upper flat edges of the slid- 15 able blades 19 and 20, respectively. The upper flat surface or area of each blade is thus always exposed to the pressure created in the outlet port by the pump, which pressure maintains the blades in constant riding contact with the rotating piston. 20 The blades 19 and 20 are also controlled and held in their proper working relations by rocking lever 24 and a compression spring 25 which is interposed between a supporting plunger 26 and an adjustable sealing nut 27 seated within the upper part of body 2. Plunger 26 is a cylindrical piece free to move 25 vertically in a round bore in body 2, and spring 25 is seated within a recess in the upper end of this plunger, while its lower end is bifurcated to receive the flat-sided rocking lever 24. An axial passage 26' in the plunger permits the fluid under pressure to pass upwardly into the space beneath nut 27 so as to equalize the pressure on this part, 30 and the bifurcated portions of the plunger are grooved transversely to receive and rest astride a short trunnion or a pivot shaft 28 located mid-length of rocking lever 24, thereby positioning this lever centrally in respect 35 to the slidable blades so that the rounded ends 29 thereof rest upon the smooth flat upper edges of said blades. The plunger is prevented from turning and the lever also held upright in parallel alignment with both 40 slidable blades by providing a depending boss 30 centrally within compartment 18, and slotting this boss 30 vertically and radially thereof to receive and confine the opposite ends of the lever. In effect the upper end of body 2 is slotted so that lever 24 can work freely but not tilt laterally nor be 45 displaced or unseated, even though nut 27, spring 25 and plunger 26 are bodily removed from body 2 when inspection or repairs of 50 these parts are undertaken.

A by-pass passage 31 is also provided in head 11 between the inlet and outlet ports of the pump, which passage contains a spring- 55 pressed valve 32 adapted to open and permit the fluid to circulate through the pump should the discharge be checked or cut-off while the pump is running. The pump also includes a strainer 33 in the intake 34, but as these features are fully described in the co-pending application referred to herein,

further, detailed description thereof is unnecessary and will be omitted herefrom.

What I claim, is:

1. In a rotary pump, a body having an inlet and outlet, circular chambers in open communication with said inlet and outlet, slots extending radially from said chambers, fluid passages extending from said outlet centrally to said slots, a compartment open to said slots, a slotted boss extending into said compartment and a cylindrical bore extending through said body from the outside and through said boss to said compartment in the plane of said slots. 70

2. A rotary pump, comprising a body having circular chambers, rotary pistons situated eccentrically within said chambers, reciprocable solid blades engaging said pistons, a vertically shiftable pivoted equalizing lever supported by said blades, yielding devices to force said lever toward said blades, and a slotted boss integrally formed with said body for guiding said yielding devices and the central portion of said lever and holding said lever in its normal working position when said yielding devices are removed. 80

3. A rotary pump, comprising a body having a pair of circular working chambers separated by a central division wall, said body also having a compartment and vertical slots connecting said compartment and said chambers, said body being further provided with a slotted boss extending into said compartment and separate inlet and outlet ports communicating with said working chambers adjacent the slots, a pair of rotatable pistons eccentrically mounted within said circular chambers, a pair of abutment blades slidably confined within said slots and engaging said pistons, said body having a bore within said slotted boss, communicating with said compartment, a shiftable equalizing lever slidably confined within the slots of said boss having a pivot shaft mid length thereof and supported at its opposite ends upon said blades, a bifurcated plunger having opposite slots arranged axially shiftable within said bore and separably engaging the pivot shaft of said lever for pivotal support thereof, a compression spring seated within said bore against said plunger, and means detachably connected with said body and bearing against said spring. 95

In testimony whereof I hereby affix my 100 signature.

JOSEPH F. JAWOROWSKI.
